UNITED STATES PATENT OFFICE

WALTER C. FAIN, OF NORFOLK, VIRGINIA

CONCEALABLE FURNISHINGS

Application filed March 12, 1924. Serial No. 698,792.

This invention relates to improvements in concealable house furnishings and more particularly to a dining set for installation in apartments where the space is restricted, 5 the primary object of the invention being to provide a dining set which may be readily installed in an offset in a wall of an apartment room and which, when not in use, may be folded and concealed from view and, on the other hand, when required for use, may be readily and conveniently set up.

One of the important objects of the invention is to provide a dining set comprising a table and benches all contained within 15 a single housing and normally concealed from view, the arrangement being a compact one so as to occupy a minimum space and yet being such as to permit of ready arrangement for use.

20 Another object of the invention is to provide, in concealable furnishing of this character, a maximum table area and maximum seating capacity as regards the benches, and to so arrange the component parts of the 25 structure that when not in use they will occupy a space of considerably less width than the space occupied by the component parts when the structure is in use.

It has been proposed heretofore to construct concealable furnishings of this class embodying a cabinet having hinged doors, and table or other units foldably mounted within the cabinet so that when the doors are opened the units may be lowered to assume a position for use, but in such structures the doors serve solely the purpose of doors. In other words, they serve merely as means for concealing from view the interior of the cabinet and the parts which are housed therein, when such parts are not in use. Therefore, it is another object of the present invention to utilize the doors of a structure of this class as a means for supporting the bench units so that the units may be lowered to position for use after the doors have been swung open and will at such time assume positions at opposite sides of the table unit, the doors constituting the sole support for the bench units when the bench 40 units are folded up and are not in use. By

this arrangement the invention, therefore, contemplates housing the table and bench units within a cabinet or compartment of a width substantially not greater than the width of the table unit. Likewise, by reason of this arrangement, the invention contemplates the employment of narrower doors than could otherwise be used thereby effecting a further economy in space and likewise in the cost of the doors.

Another object of the invention is to provide novel means for supporting the outer ends of the bench units when the units are set up for use, which means may be conveniently folded with respect to the seats of the bench units and occupy minimum space.

Another object of the invention is to provide a novel form of back for each bench unit and a novel means for holding the back in set up position when the unit is arranged for use.

A further object of the invention is to provide means for relieving the doors of the structure from strains to which their hinges would otherwise be subjected during the time the bench units were in use.

Another object of the invention is to provide means for assisting in elevating the table and bench units to folded position within the compartment.

Another object of the invention is to so construct the compartment that food may be served from the adjoining kitchen onto the table unit of the furnishing without the necessity of passing back and forth between the two rooms, or, in other words, back and forth between the kitchen and the room in which the structure of the present invention is located.

In the accompanying drawings:

Figure 1 is a view in front elevation of a concealable furnishing embodying the present invention, the doors of the structure being swung open and the table and bench units being set up for use;

Figure 2 is a vertical front to rear sectional view through the structure, the table and bench units being set up for use;

Figure 3 is a similar view illustrating the

structure completely folded and the doors thereof closed;

Figure 4 is a horizontal sectional view through the structure taken substantially on the line 4—4 of Figure 2 looking in the direction indicated by the arrows;

Figure 5 is a horizontal sectional view taken substantially on the line 5—5 of Figure 2, in detail;

10 Figure 6 is a similar view in detail taken substantially on the line 6—6 of Figure 2;

Figure 7 is a detail vertical sectional view through a portion of the table unit and illustrating the means provided for assisting in 15 the elevation of this unit to its folded position.

As heretofore stated, the structure embodying the invention is housed within a compartment or cabinet which in turn is 20 set or built into the wall of the room in which the furnishing is to be employed, the wall being indicated by the numeral 1, and, as a matter of convenience, being shown of solid construction, although, of course, it 25 will be built up in any of the numerous ways well known. The wall is provided with a recess which is indicated by the numeral 2 and which is of sufficient height, width and depth to accommodate the cabinet or compartment of the furnishing which 30 cabinet or compartment is indicated in general by the numeral 3. The cabinet 3 comprises side walls 4, a back 5 which may be of veneer or any other material found suitable for the purpose and relatively thin, and a top 6, and the cabinet is of substantially rectangular form and is fitted snugly into the recess 2 in the wall 1, cleats 7 being secured to the rear wall 5 of the cabinet to 35

40 space the said wall a short distance in advance of the back wall of the recess, which wall of the recess is indicated by the numeral 8. Except for the doors which are to conceal the table and bench units when the 45 units are not in use, the cabinet is open at its front, and a facing 9 is constructed about the open front of the cabinet and the open front of the recess 2 in the wall 1 so as to impart the required finished appearance.

50 The doors of the cabinet are indicated by the numeral 10 and the said doors are hinged, as at 11, to the opposite sides of the open front of the cabinet and are adapted to be swung to the open position shown in

55 Figures 1 and 4 of the drawings or to the closed position shown in Figure 3. At this point it is pertinent to note that when the doors 10 are swung to open position as shown in Figure 4 of the drawings, they will

60 rest at their normally outer sides against the side members of the facing 9 and will therefore occupy a position precisely parallel to the face of the wall 1 at opposite sides of the recess 2 in the said wall, the leaves

65 of the hinges 11 being of such width and

the facing 9 being of such thickness as to insure of such positioning of the doors.

As heretofore pointed out, the invention contemplates the provision of a table unit which is indicated in general by the numeral 12, and bench units which are indicated in general by the numeral 12', the table unit 12 being connected with the rear wall or back 5 of the cabinet, and the bench units being connected with the doors 10, each 70 in a manner which will now be explained. The table unit 12 comprises a top 13 which may be of any desired dimensions and this top is hingedly connected, as at 14, to a cleat 15 secured to the inner face of the wall 5 of the cabinet. Moulding strips 16 are secured to the under side of the table top 13 along the longitudinal edges thereof and across the outer end edge and add to the ornamental appearance of the structure and 75 likewise serve a purpose to be presently explained. At this point it will be understood that the table top 13 may be swung downwardly to assume the position shown in Figure 2 of the drawings, when the table is to 80 be used, at which time the inner end edge of the said top will abut against the face of the cleat 15, and by reference to Figure 4 of the drawings it will be observed that the cabinet is of a width just sufficient to 85 accommodate the table unit 12 so that the said table unit may be swung upwardly about its hinges to assume a position resting at its upper portion against the face of the rear wall 5 of the cabinet as shown in Figure 3, the said table unit being in this manner more or less snugly received within the 90 cabinet and an economy in space being effected.

In order that the outer end of the table 95 top 13 may be firmly supported when the table unit is lowered to position for use, a supporting leg 17 is hingedly connected at its upper end, as at 18, to the under side of the said table top 13 at the said end thereof. Brace members 19 are pivotally connected at their upper ends, as at 20, to the inner sides of the side moulding pieces 16 and have their lower edges notched, as at 110 21, near their outer ends so as to engage with studs 22 upon the leg member 17 when the leg member is swung down to supported position as shown in Figure 2, the braces 19 being in this manner locked in bracing position and serving to prevent inward and 115 upward swinging movement of the said leg member 17. By reference to Figure 3 of the drawings it will be observed that the leg 17 of the table unit may be folded to position lying flat against the under side of 120 the table top 13 and that in this position the said leg will lie substantially within the bounds of the moulding pieces 16.

In order that the table unit 12 may be 125 more or less counter-balanced and its up-

ward swinging movement to folded position effected without any considerable exertion, means are provided which will now be described. The means referred to are best illustrated in Figure 7 of the drawings and comprises an arcuate barrel 23 which is of tubular form and is closed at one end by an attaching plate 24 by which it is secured at the said end to the wall 1, the said barrel extending through the rear wall 5 of the cabinet 3 and curving upwardly and forwardly within the said cabinet. An arcuate arm 25 having the same degree of curvature as the barrel 23, is secured at one end, as at 26, to the under side of the top 13 of the table unit 12 near the hinges 14, and the said arm works slidably in the bore of the barrel 23 as shown in the said Figure 7, the barrel and arm being concentric with the hinges 14. A compression spring 27 is arranged within the barrel 23 and bears at one end against the attaching plate 24 and is engaged at its other end by the extremity of the arm 25. At this point and by reference to Figure 7, it will be understood that as the top 13 of the table unit is swung downwardly about its hinges 14, the arm 25 will ride in the bore of the barrel 23 and compress the spring 27, the resistance offered by the spring substantially counter-balancing the weight of the unit 12. Thus the table unit may be lowered to position for use without any sudden jar, and, on the other hand, when it is to be stored away, it may be swung upwardly about its hinges with little exertion due to the counter-balancing effect of the spring 27.

Each of the bench units 12' comprises a seat 28, a back 29, and an end 30. The seat 28 is connected at its inner end by hinges 31, to the normally inner face of the respective door 10 at such elevation that when the bench unit is set up for use, the seat 28 will occupy a plane suitably spaced below the plane of the top 13 of the table unit. The back 29 of each bench unit may be of any suitable design and is hingedly connected at its lower edge, as at 33, to the upper side of the seat 28 along the outer longitudinal edge thereof, the back being designed to be swung downwardly to lie flat against the normally upper side of the seat 28, when the structure is not in use, and being designed, on the other hand, to be swung upwardly to a vertical position perpendicular to the seat 28 when the structure is in use. In order that the back 29 may be braced in this latter position, a short length of angle iron 34 has one of its wings secured, as at 35, to the normally inner face of the respective door 10, its other wing, indicated by the numeral 36, being somewhat narrower than the attached wing referred to and constituting a stop or abutment against which the end of the back 29 next adjacent the door

may engage when the back is swung to upright position. A slideable bolt of the well known type illustrated in Figure 6, is mounted upon the inner face of the back 29 and may be shifted to project its working end into an opening 38 formed in the attached wing of the angle iron 34. In this manner the back 29 at its said end is secured both against forward and rearward displacement.

The end member 30 of the bench unit may be of any desired marginal contour or outline and is shown most clearly in Figures 1 and 2 of the drawings. The said end member 30 may be of integral structure or built up of a number of assembled parts, but in any event it is to be considered as an integral unit and it is to constitute not only a supporting means or leg for the outer end of the respective seat 28 but also is to constitute an arm rest as will be apparent by reference to Figure 1. The said member 30 is connected for folding movement with the outer end of the seat 28 by hinges 39 the leaves of which are secured to the inner side of the said member at a point suitably spaced from its upper and lower ends, and to the under side of the said seat 28 at the said outer end, thereof.

It will now be evident and particularly by reference to Figure 2 and a comparison of this figure with Figure 3, that the end member 30 is hinged in such a manner that it may be swung about its hinges to assume a position with its lower or leg portion, which is indicated by the numeral 40, resting flat against the under side of the respective seat 28, and with its arm rest portion or upper portion, indicated by the numeral 41, projecting a short distance beyond the said outer end of the said seat. Braces 42 corresponding in function and construction to the braces 19 heretofore described, may be employed at the outer ends of the bench units to relatively brace the end member 30 and the seat 28 and prevent inward swinging movement of the lower portion of the said member 30. Likewise counter-balancing means indicated in general by the numeral 43 and corresponding in every respect to the means shown in Figure 7 and previously described, may be employed for the purpose of assisting in elevating the bench units to their folded position which is clearly illustrated in Figure 3 of the drawings, the back 29 of each unit being folded in to lie against the upper side of the seat 28, and the member 30 being folded in so that its lower or leg portion 40 will rest against the under side of the said seat.

In order that the back 29 and the end member 30 may be relatively braced against displacement when the structure is set up for use, a latch 44 is pivotally mounted, as

at 45, upon the inner side of the back 29 and has a shouldered end 46 which is engageable through an opening 47 provided in a keeper plate 48 secured upon the inner side of the said end member 30. The opposite end of the latch 44 is turned outwardly to provide a finger piece 49 against which pressure may be exerted, against the tension of a leaf spring 50 arranged in back 10 of said finger piece, to disengage the shouldered end of the latch from the wall of the opening 47 and thus permit of relative displacement of the members 29 and 30.

In order that the hinges of the doors 10 may be relieved to a considerable extent, of the weight which would otherwise be imposed upon them during the time the bench units are occupied, supporting legs 51 are hingedly connected at their upper ends, as 20 at 52, to the under side of the respective seats 28 and may be swung downwardly to the position shown in Figure 2 of the drawings so as to rest at their lower ends upon the floor of the room, in which position their 25 upper ends will abut squarely against the under side of the respective unit. When the bench units are folded up, the supporting legs 51 may be swung upwardly about their hinges 15 so as to rest against the 30 under sides of the respective seats 28.

From the foregoing description of the invention it will be evident that the table and bench units may be swung downwardly so as to assume the positions shown in Figures 1, 2 and 4 of the drawings, in which the bench units occupy positions at opposite sides of the table unit. On the other hand, when the structure is not to be used, the several units may be folded up in the manner heretofore outlined, and the table unit 40 swung upwardly to position resting against the back wall 5 of the cabinet, the bench units being swung up to lie against the inner sides of the respective doors 10, whereupon the doors may be closed so as to completely conceal the folded units.

Means has hereinbefore been described for relieving the hinges of the doors 10 of the weight which would otherwise be imposed upon them if it were not for the legs 51. As a means for further serving this end and at the same time providing against any swinging movement of the doors while the bench units are occupied, 50 door stops 53 are mounted upon the normally inner face of the doors 10 at their free edges and the rubber foot pieces 54 of the said stops are designed to firmly engage the floor surface when the plungers of 60 the stops are pressed downwardly in the usual manner.

It will be evident that when the table and bench units are folded and the doors are closed, the structure will have a maximum 65 width not appreciably greater than the

width of the table top 13 and consequently the furnishing will occupy but a small area of the wall surface of the room.

If desired, as a matter of convenience, to obviate the necessity of passing back and forth between the kitchen and the room in which the furnishing is arranged, a serving window may be provided as illustrated most clearly in Figures 1, 2, 3 and 4 of the drawings. In providing the serving window, 70 an opening 55 of oblong rectangular form is cut in the rear wall 5 of the cabinet and extends transversely across the said wall, immediately above the plane of the table top 13, and a similar opening 56 is cut in the wall 1 opposite the opening 55, cleats 57 and 58 being arranged between the said wall 1 and the wall 5 and respectively above and below the openings 55 and 56. The opposing edges of the cleats 85 are grooved, as indicated by the numeral 59, and a door 60 is mounted within the opening of the window and has beads 61 extending along its upper and lower edges and slidably fitting in the grooves in the cleats 90 57 and 58, respectively. The door 60 is provided with knobs 62 whereby it may be conveniently slid to and from its open and closed position, and the said door is of a width substantially equal to one-half the 95 length of either opening 55 or 56. A frame of moulding, indicated by the numeral 63, is arranged about the opening 55 and upon the face of the wall 5, and when the door 60 is closed, it will occupy substantially one-half of the frame, the other half of the frame being occupied by a permanent panel 100 64 and the said panel and door being similarly finished so that there will be as little resemblance as possible to a sliding door structure. A shelf 65 is preferably mounted upon the wall 1 at that face in which the opening 56 is formed and extends across the lower side of the said opening and serves 105 as a support for dishes containing food which may be placed thereon prior to being passed through the opening provided when the door 60 is slid to open position.

Cleats 13' and 28' are secured respectively to the back wall of the cabinet and to the inner faces of the doors 10 below the hinges 14 for the table top 13 and the hinges 32 for the seats 28, and serve as additional supports for the hinged ends of these parts.

Having thus described the invention, what 110 is claimed as new is:

1. In concealable furnishings, a cabinet having a rear wall and an open front, doors for closing the front of the same, a seat unit pivoted at its end to one of said doors and foldable within said cabinet, a supporting member for the outer end of said seat hingedly connected therewith intermediate the length of said supporting member and foldable partially to underlie said seat, said 125

supporting member when in open position projecting as to its upper portion above said seat to constitute an arm rest, a supporting leg pivoted to the underside of said seat near its end adjacent said cabinet for supporting the same independent of said cabinet, and a back for said seat foldably connected therewith and adapted when folded to lie against the upper side thereof.

2. In concealable furnishings, a cabinet having a rear wall and an open front, a door hinged to one side of the front of the cabinet, and a bench unit associated with the said door, said bench unit comprising a seat foldably connected with said door, a back foldably connected with said seat, an end supporting member foldably connected with said seat at the outer end thereof and having an arm rest portion adapted to extend above the plane of the seat when the bench unit is set up for use, and coacting means upon the said arm rest portion of the supporting member and upon the said back for relatively bracing the parts.

3. In concealable furnishings, a cabinet having a rear wall and an open front, hinged doors for closing said front of the cabinet, a table unit of substantially the width of said cabinet and foldably connected with said rear wall, bench units foldably connected endwise with the inner faces of said doors and adapted, when said doors are open parallel with the face of the cabinet, to be projected to each side of the lateral limits of said cabinet and parallel with said table, supporting members at the outer ends of said bench units hingedly connected therewith and foldable to lie against the underside thereof, and backs for said bench units foldably connected therewith and adapted when folded to lie against the upper sides thereof.

4. In concealable furnishings, a cabinet having a rear wall and an open front, a table unit foldably connected with said rear wall, bench units, means pivotally connecting said bench units endwise to said cabinet to swing about horizontal axes, said bench units being adapted to be folded in said cabinet or to be projected from said cabinet parallel to the table, supporting members at the outer ends of said bench units hingedly connected therewith and foldable to lie against the under side thereof, said supporting members extending above the plane of the seats when the bench members are set out for use, backs for said bench units foldably connected therewith and adapted when folded to lie against the upper sides thereof, and coacting means upon the upwardly extending portions of the supporting members and upon the backs for supporting the backs in raised position.

In testimony whereof I affix my signature.
65 WALTER C. FAIN. [L. S.]
